UNITED STATES PATENT OFFICE

138,357

DESIGN FOR A PEPPER SHAKER

Boris Trifonoff, East Liverpool, Ohio, assignor of fifty per cent to George E. Marsh, East Liverpool, Ohio

Application April 19, 1944, Serial No. 113,307

Term of patent 7 years

(Cl. D44—22)

To all whom it may concern:

Be it known that I, Boris Trifonoff, a citizen of the United States, residing at East Liverpool, in the county of Columbiana and State of Ohio,
have invented a new, original, and ornamental Design for a Pepper Shaker, of which the following is a specification, reference being had to the accompanying drawing, forming part thereof.

Figure 1 is a front elevational view of a pepper
shaker, showing my new design;

hand side of Figure 1;

Figure 6 is a bottom plan view thereof.

I claim:

The ornamental design for a pepper shaker, as shown.

BORIS TRIFONOFF.
